US00D935090S

(12) **United States Design Patent** (10) **Patent No.:** **US D935,090 S**
(45) **Date of Patent:** **** Nov. 2, 2021**

(54) **PORTION OF A LUMINAIRE**

(71) Applicants: **Marthinus Christoffel Van Der Schyf**,
Austin, TX (US); **Jonathan Becker**
Schmidt, Round Rock, TX (US);
Kenneth B. Frame, Spring, TX (US)

(72) Inventors: **Marthinus Christoffel Van Der Schyf**,
Austin, TX (US); **Jonathan Becker**
Schmidt, Round Rock, TX (US);
Kenneth B. Frame, Spring, TX (US)

(73) Assignee: **Fluence Bioengineering, Inc.**, Austin,
TX (US)

(**) Term: **15 Years**

(21) Appl. No.: **29/699,998**

(22) Filed: **Jul. 30, 2019**

(51) LOC (13) Cl. **26-05**

(57) **CLAIM**

The ornamental design for a portion of a luminaire, as shown and described.

DESCRIPTION

FIG. 1 is a side perspective view of the new design for a portion of a luminaire;

FIG. 2 is an enlarged detail right side elevational view of FIG. 1 thereof with a portion removed for clarity of illustration;

FIG. 3 is an enlarged detail left side elevational view of FIG. 1 thereof with a portion removed for clarity of illustration; FIG. 4 is a right end elevational view thereof, the left end view being the same;

FIG. 5 is an enlarged detail bottom plan view of FIG. 1 thereof with a portion removed for clarity of illustration; and,

FIG. 6 is an enlarged detail top plan view of FIG. 1 thereof with a portion removed for clarity of illustration.

The broken line disclosure represents portions of the portion of a luminaire that form no part of the claimed design.

1 Claim, 6 Drawing Sheets
